United States Patent Office.

JONATHAN BUNDY, OF WEST LIBERTY, IOWA.

Letters Patent No. 78,051, dated May 19, 1868.

IMPROVED MODE OF CONSTRUCTION OF PEAT-CARS.

The Schedule referred to in these Letters Patent and making part of the same.

TO ALL WHOM IT MAY CONCERN:

Be it known that I, JONATHAN BUNDY, of West Liberty, in the county of Muscatine, and State of Iowa, have invented certain new and useful Improvements in Devices for Conveying and Discharging Peat; and I do hereby declare that the following is a full, clear, and exact description thereof, reference being had to the accompanying drawings, and to the letters of reference marked thereon, which form a part of this specification, in which—

Figure 1 represents a plan view of my car when placed on the rails.

Figure 2 is an end elevation of the car with windlass attached.

Figure 3 is a transverse section of the same.

The object of my invention consists in a new method of conveying, discharging, and moulding peat.

The car which I use is constructed as follows: A represents the body of the car, the sides and ends of which are made to incline slightly inwards. C designates the wheels, which are placed fore and aft the car-body for reasons that will be hereafter set forth.

In front of one pair of car-wheels, and in the rear of the other pair, are placed the vertical boards D, which extend out as far as the flange on said wheels, and are designed as shields to prevent the peat, when discharged at the bottom of the car, from obstructing the wheels.

E E represent two trap-doors hinged at their outer edge to the lower side rails of the car. G is a shaft pivoted in the ends of the car, and placed immediately above the line at which the trap-doors meet. One end of shaft G is furnished with the crank, H.

To the shaft G are attached the four cords s s s, the opposite ends of said cords being fastened to trap-doors E, two to each door.

In order to keep the shaft G in any desired position, the bar m is provided, which is confined at its ends by the staple-shaped metal plates n n. A pin is inserted through each plate, n, and through bar m. By this arrangement either end of bar m can be lowered when required.

In the centre of bar m a depression is made, into which the lower end of crank H is designed to fit, so as to prevent the said crank from turning when the car is loaded.

M represents a movable railroad, which can be transferred to any desired point. N designates a portable turn-table, which will be used when the car is to be run on rails at right angles with the main track.

It will be observed that the side rails and tier of my railroad will form moulds for the peat when it is discharged from my car.

In operating my car, it will be run under the peat-reservoir, and the gate of the reservoir being drawn, the plastic peat issues and fills the car. The gate being then closed, the car will be moved on by horse-power, and when it reaches the movable and moulding-track M, the portable turn-table will be adjusted to the desired position, and by its operation the car will be transferred to said track M.

When the car has arrived at track M, one pin will be withdrawn from the end of bar m, and by the descent of one end of said bar the crank, H, will be released, and the weight of the peat pressing on the trap-doors E E will cause them to open downward, and thereby discharge the peat into the moulds formed by the rails and tier of the movable track, as already described.

It will be remarked that when the first mould is filled, as the car advances, the front board D will force the surplus peat forward to the next mould, and so on until the car is exhausted of its contents.

It will be further observed that the trap-doors E E, being pressed down by the weight of the peat in the car, will compress the peat within the successive moulds, so as to give it greater consistency.

Having thus described my invention, what I claim, and desire to secure by Letters Patent, is—

The car A, provided with hinged bottom E E, when combined with the shaft G, cords or chains s s, bar m, and lever H, all arranged as and for the purpose set forth.

In testimony that I claim the foregoing as my own, I affix my signature in presence of two witnesses.

JONATHAN BUNDY.
